SAMUEL E. TURK, OF MINDEN, LOUISIANA, ASSIGNOR OF ONE-HALF TO MARTIN SPIERS, OF BARTH, MISSISSIPPI.

LANTERN DOME.

Application filed August 29, 1928. Serial No. 302,872.

This invention relates to lanterns, embodying among other characteristics, a ventilator adapted to discharge smoke and heat emitted therefrom.

5 Another object of the invention contemplates locking means connecting a globe retainer which may be readily disassembled from the ventilator when partially rotated.

With the above and other objects in view, 10 the invention further includes the following novel features and details of construction, to be hereinafter more fully described, illustrated in the accompanying drawing, and pointed out in the appended claim.

15 In the drawing:

Figure 1 is a vertical section taken through the ventilator and retaining means.

Figures 2 and 3 are sectional views taken on lines 2—2 and 3—3, respectively, of Figure 1. 20 A dome-shaped cover or lid 14 is provided with a combined ventilator and globe retainer. An inner dome 15 is positioned within the dome-shaped member 14 and insulated therefrom by a packing 16, such as asbestos. Both 25 of the dome-shaped members are foraminated. The globe retaining plate 17, provides an annular seat 18 upon its under side and is positioned within the inner dome-shaped member 15. Intersecting cross bars 19 pass 30 through an eye 20 provided in the lower end of a rod 21 which in addition supports a frustoconical shaped smoke deflector 22. The upper end of the rod 21 also provides a looped end 23 adapted for selective engagement with 35 an offset pin 24 suspended and depending within the dome-shaped member 14. Said end is passed through a slotted portion in the upper portion of the inner dome-shaped member 15. A coil spring 25 encircles the rod 21 40 and has its opposite end convolutions engaging the inner dome-shaped member 15 and periphery of the globe retaining plate 17.

A slight twist of the dome-shaped member 14 and globe retaining plate 17 in opposite directions, when the latter compresses the spring 45 25, will release the upper looped end 23 of the rod 21 from the offset finger 24 suspended and depending from the dome-shaped member 14.

Manifestly, the height of the lamp or lantern, would naturally tend to overheat the 50 dome-shaped member 14, which oftentimes burns the hands when a swinging handle is employed. The inner dome-shaped member 15 is insulated from the outer dome-shaped member and each of which provides foraminated side walls through which smoke and 55 heat may pass, will overcome this difficulty and, hence, the lamp may be carried with ease.

This invention is susceptible to various 60 changes in its form, proportions and minor details of construction, and the right is herein reserved to make such changes as properly fall within the scope of the appended claim.

Having thus described my invention, I 65 claim:

A lantern having inner and outer dome-shaped members, said inner member having a slot within the upper end thereof, said members being telescopically associated and foraminated, a globe retaining plate carried 70 within the inner member, a compression spring interposed between the inner dome-shaped member and retaining plate, cross bars carried by the retaining plate, a rod engaging the intersecting portion of the cross bars for 75 supporting the retaining plate against the tension of the spring, and said rod having an enlarged portion passing through the slot in the inner dome.

In testimony whereof I affix my signature.

SAMUEL E. TURK.
